[57] ABSTRACT

A platform for use with a steel mill on which to stack steel plate or billets is provided with hydraulic rams to raise and lower the platform, and has a pair of pivoting side links to stabilize the platform against side thrust when billets are slid thereon, the stability of the platform against canting being provided by a downwardly extending moment arm having a pivotal linkage attached to the bottom and thereof, and a synchronizing shaft connecting a pair of the stabilizing linkages to prevent relative twisting therebetween.

SHEET 2 OF 2

SLAB PILING SYSTEM

This invention is directed to a load elevator, and in particular to an elevator for stacking steel slabs in a steel mill.

In the operation of a steel mill, slabs moving along the roll tables are assembled in stacks for pick-up and transportation by crane. The stacking of the slabs is normally effected using a slab elevator positioned beside the roll table, with slab pushers being used to slide the slabs sequentially onto the elevator and the height of the elevator being progressively reduced by the thickness of the slab to ensure easy slide-on of the succeeding slab.

The slab elevators of the prior art generally use mechanical rams driven by threaded nuts, the application of transverse forces being resisted by slide guides.

Owing to the adverse nature of mill environment, such as high temperatures and in particular the presence of scale, etc. the prior art mechanisms are very subject to undue wear, while at the same time having a high initial cost. The operation of such prior art arrangement is further complicated by the necessity of synchronizing the individual drives to the raising spindles in order to prevent canting of the elevator platform.

The present invention provides a simple robust platform elevator using hydraulic rams to control the elevation of the platform. Pivoted links that are substantially immune to adverse mill conditions are used to provide transverse restraint of the platform under loading forces and to stabilize the platform against canting and tipping.

In addition to providing simple robust mechanisms that are substantially unaffected by mill conditions, the present invention provides platform installation system of very low cost, in that hydraulic jacks suitable for this use are not a high-cost item, and the energizing requirement for raising the platform can be met by the use of an electric motor and pump of comparatively small size in combination with a suitable pressure accumulator.

In addition to the foregoing advantages, in operation the present invention has the particular attribute that the rate of lowering of the platform for the reception of a further plate or billet is dependent only upon the function of the control valve through which the hydraulic rams are bled to drain. Thus, the capability of rapid realignment of the top surface of a plate on the loaded platform with the surface of the table rolls ensures a minimum delay in the transference of slabs successively to the piler.

The present invention thus provides platform apparatus for vertically positioning heavy loads, comprising: substantially rigid platform means having a top surface to receive a load thereon in lateral sliding relation from a loading surface located adjacent one side of the platform means; pivotal lateral restraint means securing the platform means in lateral positioned relation relative to the loading surface; adjustable lift means to provide upward support and displacement force to the platform means in load bearing relation therewith; and stabilizing moment applying means to maintain the platform means substantially level between an upper and a lower support position.

The present invention further provides a platform apparatus including stabilizing means having a first moment applying means to preclude rotation of the platform means about a first axis, and second moment ap-

plying means to preclude rotation of the platform means about a second axis extending normal to the first axis in a horizontal plane.

The invention further provides a hydraulically elevated platform having a moment arm extending downwardly from the platform, the lower end thereof having a pivotal restraint linkage attached thereto to maintain motion of the arm along a substantially vertical path. Certain embodiments of the present invention are described, reference being made to the accompanying drawings wherein:

FIG. 1 is an end elevation in partial section of an elevator platform according to the present invention; and

FIG. 2 is a side elevation of the elevator platform.

Referring first to FIG. 1, the elevator arrangement 10 is shown installed in relation to a portion of a roll table 12 having rolls 14 extending beside the elevator 10 by means of which a slab 16 can be positioned adjacent the elevator platform. Such a slab 16 shown chain dotted is illustrated as having been slid sideways partially off the rolls 14 in loading relation towards the elevator 10, shown chain dotted in its uppermost raised position, having the upper faces 18 of the table ribs 20 in horizontally aligned relation with the rolls 14 of the roll table.

The elevator platform 22 comprises a plurality of ribs 20 carried by a deep section 24 having a top flange plate 26, bottom flange plate 28 and a plurality of web plates 30 extending therebetween. The spaced ribs 20 permit the use of a crane C-hook in off-loading or loading the elevator, the lower jaw of such a hook being free to enter transversely between adjacent ones of the ribs 20 in lifting relation against the bottom surface of a plate 16 supported by the rib surface 18.

A pair of lateral thrust links 32 are secured to a torque shaft 34 carried between bearings 36, and connected at pivot pins 38 to restraint lugs 40 which in turn are secured to the bottom flange plate 28 of the structure 24. A pair of extensible hydraulic rams 44 are pivotally mounted on gimbal pins 46 at about the midpoint of the length of rams 44, and pivotally attached at 48 to a jack lug 50 attached to the bottom surface of flange plate 28. The gimbal pins 46 are carried in bearings 47 on a pad 49.

Admission of pressurized hydraulic fluid in usual well-known fashion from hydraulic pump means, not shown, causes controlled raising of the platform 22. Controlled bleeding or exhaust of the hydraulic fluid provides rapid lowering of the platform 22. A downwardly extending tapered moment arm 52 of a deep T-section connects the platform 22 with a wish bone restraint link means 54, the wish bone links 54 being pivotally pinned at 56 to the moment arm 52, and attached by pivot brackets 58 and pins 60 to a suitable foundation or bolster.

The wish bone links 54 are substantially the same length as the thrust links 32 and positioned substantially parallel therewith, so that the platform rises level, through a slight arc, with the links 32, 54 being substantially horizontal at the mid-lift position. In operation the edge to edge alignment of successive plates can be maintained by controlling the stroke of the plate pushers (not shown).

The torque shaft 34 serves to stabilize the platform 22 against rocking. It will be understood that this equivalent stabilization function could be served, at least in

part by the wish bone links 54 or modifications thereof. Owing to the location of all working parts beneath the platform 22 and the extensive use of pivotted restraint means the subject elevator is highly resistant to damage from plate scale, while the synchronized operation of the twin rams 44 is relatively easily maintained.

In accordance with the provisions of the patent statutes, I have explained the principle and operation of my invention and have illustrated and described what I consider to represent the best embodiment thereof.

I claim:

1. Platform apparatus for vertically positioning heavy loads, comprising: substantially rigid platform means of deep section having a top surface to receive a steel slab thereon in lateral sliding relation from a loading surface located adjacent one side of said platform means; a pair of pivotal lateral restraint links securing the platform means in lateral positioned relation relative to said load surface; adjustable hydraulic jack means extending upwardly in direct supporting relation with said platform means to provide upward support and substantially ver-

tical displacement force to said platform means in direct load bearing relation therewith; a stabilizing rigid moment arm projecting downwardly from the platform means; restraint link means pivotally connected with the lower end of said stabilizing arm, and a torque shaft securing said pair of links in mutual parallel relation to maintain said platform means substantially level between an upper and a lower support position.

2. The apparatus as claimed in claim 1 wherein said torque shaft is secured between said pair of links outboard of said platform means.

3. Platform apparatus as claimed in claim 1 having said jack means pivotally connected to said platform means on substantially the central axis thereof, said pair of restraint links being connected to said platform means on the side thereof remote from said loading surface, said pair of links and said restraint link means being of substantially equal length and arranged in substantially mutual parallel relation.
